Primary Examiner — George J Ulsh*Assistant Examiner* — Thanh Luu Wong(57) **CLAIM**

The ornamental design for a 3D interlocking puzzle as shown and described.

DESCRIPTION

1. 3D interlocking puzzle

1.1: Front elevation view of the 3D interlocking puzzle showing my new design in a closed position of use for clarity of illustration;

1.2: Top perspective view of the 3D interlocking puzzle showing the puzzle pieces thereof in an exploded position for clarity of illustration;

1.3: Bottom perspective view thereof;

1.4: Front elevation view thereof;

1.5: Back elevation view thereof;

1.6: Left elevation view thereof;

1.7: Right elevation view thereof;

1.8: Top plan view thereof; and

1.9: Bottom plan view thereof.

The broken lines in the reproductions depict portions of the 3D interlocking puzzle that form no part of the claim.

1 Claim, 9 Drawing Sheets(56)
